CLAIM

The ornamental design for a ratchet, as shown and described.

DESCRIPTION

FIG. 1 is a perspective view of a ratchet showing my new design;

FIG. 2 is a front side view of FIG. 1 thereof;

FIG. 3 is a back side view of FIG. 1 thereof;

FIG. 4 is a first side view of FIG. 1 thereof;

FIG. 5 is a second side view of FIG. 1 thereof;

FIG. 6 is a top view of FIG. 1 thereof; and,

FIG. 7 is a bottom view of FIG. 1 thereof.

The broken lines in the figures are included for the purpose of illustrating portions of a ratchet and form no part of the claimed design.

1 Claim, 6 Drawing Sheets
